UNITED STATES PATENT OFFICE.

WILLIAM A. TRAVER, OF WEEDSPORT, NEW YORK.

ROAD-DRAG.

No. 909,966.

Specification of Letters Patent.

Patented Jan. 19, 1909.

Application filed May 11, 1908. Serial No. 432,110.

To all whom it may concern:

Be it known that I, WILLIAM A. TRAVER, of Weedsport, in the county of Cayuga, in the State of New York, have invented new and useful Improvements in Road-Drags, of which the following, taken in connection with the accompanying drawings, is a full, clear, and exact description.

This invention relates to certain improvements in road drags and is equally useful in leveling up and padding race tracks and also in making new roads and crowning or truing up old roads.

My main object is to produce a practically all steel, comparatively light yet highly efficient and durable road scraper which may be manufactured at a comparatively small cost and in which the scraper blades are interchangeable and reversible to permit the use of either edge next to the ground when one edge becomes worn or otherwise impaired.

Another object is to provide the normal top side of the drag or scraper with suitable shoes or runners projecting beyond the plane of the longitudinal edges of the scraper blades so that the entire machine may be inverted and easily drawn longitudinally along the ground or pavement over railroad tracks and other obstacles with but little resistance.

A further object is to provide the drag with opposite parallel scraper blades spaced some distance apart and curved longitudinally forming opposite concavo-convex scrapers, either side of which may be presented in advance of the other to throw the dirt from the center of the road outward or from the sides inward.

A still further object is to connect the opposite ends of either side of the drag by a chain or similar draft device to which a draft hook or similar connection may be attached at any point either centrally when it is desired to level race tracks and similar courses or near one end of the other when it is desired to bring the maximum draft or power near such end as in making gutters or crowning the road bed.

Other objects and uses will be brought out in the following description.

In the drawings—Figure 1 is a top plan of a road drag embodying the various features of my invention showing the draft device attached to the concave side. Figs. 2 and 3 are enlarged sectional views taken re-

spectively on lines 2—2 and 3—3, Fig. 1. Fig. 4 is a side elevation of one end of the drag in an inverted position showing the runners in contact with the ground. Fig. 5 60 is a detail elevation of the draft hook and link of the draft chain embraced thereby.

This drag comprises essentially a steel frame composed of opposite parallel side pieces —1—, opposite parallel end pieces 65 —2—, corner braces —3— and steel scraper blades —4—.

The side pieces —1— preferably consist of steel angle bars of similar length curved or concavo-convex horizontally from end to end with their upper flanges disposed in a horizontal position and projecting toward each other while their lower flanges project downwardly from the outer edges thereof, said bars being held a fixed distance apart 70 by the end pieces —2— and braces —3—. These end pieces —2— also consist of steel angle bars parallel with each other and of a length substantially the distance between the side bars —1—, with their lower flanges disposed in a horizontal position projecting toward each other and their upper flanges projecting from the outer edges thereof. The braces —3— are also formed of steel and are secured to the top faces of the bars —1— 80 and under sides of the bars —2— by suitable fastening means as rivets or bolts —5—, said braces being located at the inner corners or junctions of the side bars with the end bars as best seen in Fig. 1. 85

The opposite ends of the side bars rest upon and are secured to the top faces of the adjacent portions of the braces —3— which are, therefore, interposed between said side and end bars and serve to reinforce and 95 stiffen the frame against any strains to which it may be subjected, the end bars —2— being located a short distance inwardly from the ends of the side bars. 90

The blades —4— are secured to the outer 100 sides of the side bars —1— by suitable fastening means as bolts —6— and are of substantially the same length and curvature as said side bars but of greater vertical depth so as to extend some distances above and 105 beneath the side bars to which they are secured as best shown in Figs. 2 and 3, said blades being also made of steel capable of withstanding the strains to which they are subjected. These blades are removable and 110 interchangeable and invertible so that when one edge becomes worn they may be removed.

and inverted and interchanged from side to side and the other edges presented to the ground without disturbing the connections between the side and end bars of the main 5 supporting frame.

It is now clear that one of the working sides of the drag is concave or curved inwardly and horizontally from end to end while the opposite working side is curved 10 or convexed and parallel with the concave side thus permitting either side to be used according to the work required, each side being equipped with a pair of attaching elements as eyes —7— for the attachment of a 15 draft chain —8— shown in Fig. 1 as connected to the concave side of the drag.

The object in employing a chain as a draft connection is to enable the draft hook as 20 —9— to be attached at any point between the ends of the chain according to the work which it may be desired to perform, said draft hook being adapted to detachably embrace any one of the links as shown in Fig. 5. For example, when it is desired to level up 25 race tracks or any similar plain course, the draft hook —9— may be attached to the center of the draft chain —8— and the chain attached to either the concave or convex side of the drag or if it is desired to plow a fur- 30 row for forming a gutter and to throw the dirt toward the center of the road bed, the chains may be attached to the concave side of the drag and the draft hook attached to the chain near the side where it is desired 35 to plow the furrow as shown in Fig. 1. On the other hand if it is desired to throw the dirt from the center of the road toward the sides the chain may be attached to the opposite or convex side of the drag in an ob- 40 vious manner.

In order that the entire drag may be drawn over railroad tracks and other ob- 45 structions without meeting undue resistance, I provide the normal top of the frame with a series of in this instance four runners or 50 shoes —10— which are made in the form of steel straps arched upwardly at the center and secured at their ends directly to the braces —3— and outer sides of the cross bars —2—. The central portions of these shoes or runners normally project some distance 55 beyond the top of the scraper plate —4— and when it is desired to transport the entire device from one locality to another, said de- 60 vice is inverted bringing the shoes in contact with the ground whereupon the chains may be attached to the eyes —7— at either end of the drag to permit said drag to be drawn endwise upon the shoes in which case, the 65 lower edges of the scraper blades run clear of the ground as clearly shown in Fig. 4.

In order that the driver may ride upon the drag and to provide suitable means for supporting weights, I provide the drag with a 65 foot or runner board or plank —11— run-

ning lengthwise of the frame and secured at its ends substantially midway between the ends of the cross bars —2— by suitable fastening means as bolts —12—.

The operation of this device will be clearly 70 understood upon reference to the foregoing description taken in connection with the drawings, and it is evident that it has a wide range of uses not mentioned, partic- 75 ularly in filling ruts by reason of the curved form of blade which when drawn along the road bed at any suitable angle throws the dirt from the sides inwardly and slowly to- 80 ward the center where such accumulated dirt is distributed into and fills the ruts. 80

What I claim is:

1. In a drag of the class described, a frame composed of opposite lengthwise side bars and cross bars secured thereto and holding 85 said side bars a fixed distance apart, and scraper blades removably secured to said lengthwise bars, said scraper blades project- 90 ing vertically beyond the lower and upper sides of the frame.

2. In a drag of the class described, a frame composed of opposite lengthwise side bars and cross bars secured thereto and holding 95 said side bars a fixed distance apart, and scraper blades removably secured to said lengthwise bars, said scraper blades being 95 removable and invertible upon the frame whereby either of their longitudinal edges may be brought next to the ground.

3. In a drag of the class described, a frame composed of opposite lengthwise side bars 100 and cross bars secured thereto and holding said side bars a fixed distance apart, and scraper blades removably secured to said lengthwise bars, and runner shoes secured to the frame and normally projecting above the 105 upper edges of the scraper blades whereby when the drag is inverted, it rests upon the runner shoes.

4. A drag comprising parallel concavo- 110 convex side bars and transverse cross bars rigidly secured to the side bars, and concavo- 115 convex scraper blades secured to the side bars.

5. A drag comprising parallel concavo- 115 convex side bars and transverse cross bars rigidly secured to the side bars, and concavo- 120 convex scraper blades secured to the side bars, and reinforcing braces at the junctions of the side bars with the cross bars.

6. A drag comprising parallel concavo- 120 convex side bars and transverse cross bars rigidly secured to the side bars, and concavo- 125 convex scraper blades secured to the side bars, a chain attached to one of the side bars near its ends, and a draft hook adjustable along the chain.

7. A drag comprising parallel concavo- 130 convex side bars and transverse cross bars rigidly secured to the side bars, and concavo- convex scraper blades secured to the side

bars, and runner shoes secured to the normal upper side of the frame and projecting above the plane of the upper edges of said blades whereby the inversion of the drag brings the 5 runners into contact with the ground to hold the blades clear thereof.

8. A drag comprising parallel opposite concavo-convex side bars spaced apart, cross bars connecting and rigidly secured to the 10 side bars, concavo-convex scraper blades secured to the side bars, runner braces rigidly secured to the junctions of the side and cross

bars, runner shoes secured to said braces and to the cross bars, a foot plank secured to the cross bars, a draft chain secured to one of 15 the side bars near its ends, and a draft hook adjustably connected to the chain intermediate its ends.

In witness whereof I have hereunto set my hand this 6th day of May 1908.

WILLIAM A. TRAVER.
